CLAIM

The ornamental design for a flashlight holder, as shown and described.

DESCRIPTION

FIG. 1 is a perspective view of a flashlight holder showing our new design.

FIG. 2 is a right side view thereof, the left side view being a mirror image thereof.

FIG. 3 is a rear view thereof.

FIG. 4 is a front view thereof.

FIG. 5 is a bottom view thereof; and,

FIG. 6 is a top view thereof.

The broken lines in the views show environmental features which are for illustrative purposes only and form no part of the claimed design.
